UNITED STATES PATENT OFFICE

2,321,236

NURSING BOTTLE VALVE

Victor Parkin, Los Angeles, Calif.

Application November 19, 1940, Serial No. 366,202

1 Claim. (Cl. 251—119)

The primary purpose of this invention is to provide a nursing bottle valve of comparatively simple and inexpensive form which will prevent collapsing of the nipple and insure that the liquid contents will flow easily and uniformly responsive to the normal feeding effort of the child, and that no leakage will occur at the valve at any time.

Another purpose of the invention is to provide a nursing bottle valve of the character described which is disposed interiorly of the bottle for the most part if not entirely so as to avoid an outward projection on the walls of the bottle as well as any interference with the gripping or holding of the bottle by the child, or interference with the valve by the child, said valve being designed to function even when the fingers or hand of the child overlie it.

Another purpose hereof is to provide a valve of the character described which will be sanitary and need not be removed when the bottle is sterilized.

Yet another purpose of the invention is to provide a novel exceptionally small, simple and inexpensive valve such as described which may take the form of a plug insertable in a simple opening in a wall of the bottle, or may be carried in the nipple or formed as an integral part of the nipple; said valve having a vent adjacent its inner end, a passage in communication at one end with the atmosphere and leading to the vent and a normally closed valve member which responds to atmospheric pressure to open the vent and provides communication between the interior of the bottle and the atmosphere when sub-atmospheric pressure is created in the bottle as during a nursing operation.

With the foregoing objects in view, together with such other objects and advantages as may subsequently appear, the invention is carried into effect as illustrated by way of example in the accompanying drawing in which:

Fig. 1 is a fragmentary perspective view of a nursing bottle embodying my invention;

Fig. 2 is a sectional view on the line 2—2 of Fig. 1;

Fig. 3 is a sectional view on the line 3—3 of Fig. 2;

Fig. 4 is a fragmentary elevational view partly in section of a variational form of valve embodying my invention;

Figs. 5 and 6 are cross sections taken on the lines 5—5 and 6—6 respectively of Fig. 4;

Fig. 7 is a fragmentary side elevation of another form of my invention.

Referring more specifically to the accompanying drawing, one embodiment of my invention as shown in Figs. 1, 2 and 3, generally comprises a conventional nursing bottle 5, a nipple 6 fitted thereon, a small circular opening 7 in a side wall 8 near the closed end of the bottle and a valve A of special design fitted in said opening.

The valve shown in Figs. 1, 2 and 3 is in the form of a cylindrical plug-like body 9 having an axial passage 10 extending from the outer end thereof to a point near its inner end, which latter is reduced and formed with a circumferential groove 11. This reduced end is provided with one or more vent openings 12 which extend through the groove and the body transversely and register with the inner end of passage 10. An annular or tubular valve band 13 of thin soft rubber or the like surrounds the reduced end of the body 9 in the groove 11 under light tension normally closes the vents 12, said band being held in place by the groove. This valve band is of such form and nature that it will be forced outwardly from and open the vents responsive to the application of atmospheric pressure thereto through the passage 10 and vents, when a sub-atmospheric pressure is created in the bottle as during a nursing operation. This action of the tensioned valve permits atmospheric air to enter the bottle and thereby insure a steady flow of liquid through the nipple, and also prevents collapse of the nipple in that a vacuum in the bottle is prevented by this action.

If desired the valve body 9 may be provided with an annular flange 14 at its outer end, for overlying the wall 8 and margin of the opening 7. This flange is flat and slightly rounded at its outer periphery so as to provide a smooth flat surface at the outer end of the valve, and has but a slight protrusion from the wall 8. The body 9 is compressed and tensioned and thereby frictionally held in place when inserted in the opening 7.

I may provide in the flange 14 a plurality of radial grooves 15 arranged to insure communication of the outer end of the passage 10 with the atmosphere should the outer end of the valve be covered by the hand or fingers of the child.

It is now apparent that I have provided an exceptionally small and efficient valve which, like a plug, may be readily inserted in an opening in a nursing bottle such as the opening 7 here provided or any other opening, whereby to create an improved nursing bottle in accordance with

my invention. After being inserted in the opening the valve need not be removed in sterilizing the bottle, but may be removed at will for cleansing purposes.

Another form of my invention as shown in Figs. 4, 5, and 6 comprise a valve B similar to valve A constructed to be fitted within an ordinary nursing nipple 17 so as to extend with the neck of a bottle 18 as best shown in Fig. 4.

The valve B has a body 19 and a flange or head 20 through which a passage 21 extends. A plurality of openings 21' are provided in the flange to permit liquid to flow past the valve assembly and through the nipple during a nursing operation. The passage 21 opens through a vent 22 in a side of the body, into the neck of the bottle while the outer end of the passage registers with a vent opening 23 in the side of the nipple whereby atmospheric air may enter the bottle.

The flange 20 is in frictional contact with the nipple to retain the valve in place and may be formed with a circumferential groove 24 to insure registration of the passage 21 with the atmosphere vent 23 in the nipple.

The inner end of the valve body 19 is provided with a circumferential groove 25 in which is mounted a band flap valve 26 of rubber identical with the band valve 13 both as to structure and action. The valve 26 will normally close the passage 21 but will open under atmospheric pressure when a sub-atmospheric pressure is attained in the bottle, in the same manner as valve A.

It is seen that this form of valve is advantageous as it does not require forming an extra opening in the bottle. The valve remains in the nipple and is removed and replaced as a part thereof but may be removed from the nipple when desired for cleaning or other purposes. If desired the nipple may be formed with an annular shoulder 27 interiorly thereof for holding the valve B in proper position in the nipple as best shown in Fig. 4. The valve assembly B may be 45

made of plastic or any other suitable material except for the soft rubber valve band 26.

With reference to the modified form of valve shown in Figs. 4, 5 and 6 it is seen that the valve is operatively associated with and extends into the bottle although carried by the nipple, and operates in the same manner as the valve A shown in Figs. 1, 2 and 3.

Another modified form of my invention as shown in Fig. 7 takes into consideration the mounting and supporting of a valve assembly C on the interior of a side wall of a nipple 30 for introducing air into the bottle 31 in the same manner as the valves A and B shown in Figs. 1 and 4 respectively. Valve assembly C as here shown may if desired have its body 32 formed integrally with the nipple and be provided with a passage 33 opening at its inner end as at 34 interiorly of the nipple and opening at its outer end through the nipple as at 35 to the atmosphere. In a circumferential groove 36 in the body 32 is a rubber or similar elastic band valve 37 which normally closes the passage 33 but opens under atmospheric pressure to admit air into the nipple and bottle during a nursing operation in the same manner as the valves hereinbefore described.

I claim:

In a valve, a body laterally enlarged at one end to form a head having a passage extending inwardly from the periphery thereof then through the smaller portion of the body, said passage opening on one side of the smaller body portion and a flat rubber band valve surrounding the said smaller body portion and normally closing the end of the passage which opens on the side of said smaller body portion and adapted to yield to differential pressures on opposite sides thereof to permit air to flow past either edge thereof, said head having an opening therethrough at one side of the smaller body portion and being provided with a circumferential groove in the periphery thereof into which groove said passage opens.

VICTOR PARKIN.
